UNITED STATES PATENT OFFICE.

CHARLES N. FAIRCHILD, OF MILFORD, CONNECTICUT, ASSIGNOR TO FAIRCHILD LOCK CORPORATION, OF NEW CASTLE COUNTY, DELAWARE.

RETARDER FOR CIRCUIT BREAKERS.

Application filed November 17, 1924. Serial No. 750,481.

This invention relates to steering post locks and has for its principal object the provision of a coincidental lock which will prohibit a driver from locking his car and therefore 5 by shutting off the ignition current with a consequent stopping of the motor and then without withdrawing the key from the lock, returning the lock to running position with the result that while the motor is stopped 10 and the ignition is "on" or closed, the car is unlocked.

Other objects of the invention lie in specific details hereinafter described and particularly set forth in the accompanying 15 claims.

A serious objection to present day coincidental locks is the possibility of a driver leaving the car unlocked but with the motor not running. There is little danger of a 20 driver leaving his car unlocked with the motor running, for the laws of the various cities and States take care of this by applying a rather heavy penalty. The present invention concerns itself with a device where- 25 by the ignition circuit may not be opened until the key for locking the automobile is bodily removed from its lock, such lock preferably being a coincidental lock, i. e., one in which there is simultaneous operation of the 30 ignition circuit and of the automobile lock, the latter preferably of the steering post type.

In the drawings:

Figure 1 is a top plan view, partly in section looking directly down the axis of the steering post.

Figure 2 is a side elevation.

Figure 3 is a section through the rock shaft.

Figure 4 is a side view of the key, showing its protective casing.

For convenience in illustrating the invention I have shown it in connection with a specific form of coincidental lock but I wish 45 it understood that the invention is a basic one and should not be limited to any specific details here shown for the purpose of illustration but should only be limited as called for in the claims.

The main housing 27, which surrounds the steering post casing 10 in the usual fashion, is bored as at 11 to receive the barrel of an ordinary tumbler lock 12, the cylinder of 50 which carries a lever 15 which engages a pin

17 fast on the head 18 of the locking bolt 20, 55 the latter engaging the steering post 21 and preferably, though not necessarily, the quadrant tube 22 as well.

The head 18 slides freely with respect to the axis of the steering post in the cylindrical bore 25 of a hollow plug 26 inserted through the top of the housing and held in place therein by a pin 28. A spring 30 is held between the head 18 of the locking bolt and the insulating cover 31 of the plug, the latter being centrally perforated to provide a bearing for the stem 32 of the ignition circuit contact making and breaking mechanism. This stem 32 is provided with a head 33 between which and the top 31 of the plug is positioned a spring 34 normally holding the metallic cup 35, secured to the stem 32 between a pair of insulator washers 36 and 37, so as to maintain the metallic cup 35 in its lowermost position and the metal disk 40, seated on a shoulder 38 of the stem 32 and fast thereto, in contact with the outer face of the top portion 31 of the plug, this top 31 being the integral bottom of the switch box, the body of which is entirely of 55 insulating material and is secured to the main housing 27.

The operation of the lock so far described is as follows: With the parts in the position shown in the figures, that is in locked position, the driver wishes to start the car. He places the key 39 in the lock 12 and turns the cylinder thereof, in a clockwise direction. This raises the bolt 20 by means of the pin 17 so as to clear the steering post. When 60 the steering post is entirely free, but not until then, the head 18 of the bolt engages the head 33 of the stem. Further operation of the key causes the spring 34 to be compressed and causes the metal contact or cup 35 to rise into engagement with the spaced contacts 42 thus bridging the gap in the ignition circuit and closing the ignition circuit. As customary the key cannot be removed 65 from the lock while in this position, i. e., ordinary normal running position. To lock the car the key is turned in reverse direction, the first action being that the ignition circuit is broken and the second action being to lock the car. Now the objection to this is that the driver, if he so wills, may at this time after allowing the engine to stop, throw the lock back to unlocked position and while 70 75 80 85 90 95 100 105

the ignition circuit is again closed the motor is still but the car is unlocked and this is a thing to be avoided.

In order to prevent the opening of the 5 ignition circuit upon locking the car and before the key is removed I provide a stop rod 50 which, when the car is unlocked, is shot beneath the disk 40 fast on the stem 32, and is positively held in such position until 10 the key is removed from the lock after locking the automobile. The mechanism by which this is accomplished is as follows: A small casing 52 is secured to the main housing 27 by means of the screws 53 or similar 15 fastenings and receives longitudinally a rock shaft 55 provided with a round collar 54 to prevent its lateral movement in a direction to the left as seen in Figure 3. This shaft 55 has a square extension 56 on which 20 is loosely mounted the lever 57 which has a slotted pivotal connection with the stop rod 50.

Due to the different sizes of the square hole in the lever 57 of the square section 56 25 of the rock shaft 55, the lever 57 has a considerable play on the rock shaft which lost motion is taken up by a spring 58 secured at one end to the lever and at the other end to a cap 60 fast on the shaft and serving to 30 position the lever 57 against the collar 54. A rock arm 62 is also fast on the rock shaft 55 and carries a toe 63 to engage the key in running position. The casing 52 is provided with a bore 65 to receive a spring 66 35 serving to urge the rock shaft 55 into position to withdraw the stop rod 50 when the rock arm 62 is in the position it occupies when in running position.

A pin 67 fast with respect to the housing 40 is received in a slot 68' in the rock arm and thereby limits movement of the shaft 55. The rock arm is moved about its pivot, the axis of rock shaft 55, by means of the finger piece 68 when it is desired to move the key 45 to locking position. When in locked position a corner 69 of the arm engages the key and the rock arm is thus prevented from moving into position to turn the lever 57 to an extent that would retract the stop rod 50.

When however, the key is entirely withdrawn from the lock, the finger piece 68 is free to move to the right to the end of its travel as seen in Figure 1 and in this position the square portion of the shaft engages the square hole in the lever 57 and withdraws the stop rod 50 from beneath the disk 40 thereby permitting the cup contact 35 to 55 break the ignition circuit.

In normal operation of the automobile, the driver finds his vehicle with the ignition circuit off, the steering post locked and the rock arm 62 in position to obstruct the key hole. The finger piece 68 is first moved 60 to position to free the hole, the key then in-

serted and turned to unlocking position. This simultaneously unlocks the steering post, closes the ignition circuit and automatically restores the rock arm to its spring pressed "safety-first" position where it 70 serves to prevent the unintentional locking of the car while the vehicle is in motion, as is required by the underwriters.

To lock the car it is necessary to move the rock arm by hand to the other limit of its 75 travel as otherwise the edge of the key would be stopped by the corner 70. The rock arm may be held conveniently by the thumb of the left hand while the key is turned counter-clockwise by the right hand 80 to locking position. Such movement of the lock cylinder may however only lock the car and will not break the ignition for the cup contact member 35 is held against movement under the urge of its spring 34 by means of 85 the stop rod and this in turn is held against the urge of its spring 58 by the positive engagement of the lever 57 with the rock shaft 55.

Withdrawal of the stop rod 50 can only 90 be accomplished by outward movement of the top of lever 57 and this in turn is prevented while the key stays in the lock because the presence in the keyhole of even the tip of the key will prevent the rock arm 62 95 from completing its upward movement. When the key is entirely withdrawn, however, the rock arm under tension of its spring 66 moves to the upward limit of its travel and the rock shaft 55 moves to withdraw the stop rod 50 and thereupon the spring 34 urges the head 33 downward toward the head of the bolt thus breaking the ignition circuit.

It will be understood that when the steering post is unlocked and the stem 36 is raised by contact of the head 18 of the bolt, the spring 58 will shoot the stop rod 50 under the disk 40 as soon as it is raised since there is sufficient play between the lever 57 and the rock shaft to permit this action.

While it is stated that it is convenient to use both hands in unlocking the car this is not at all essential as by holding the key between the thumb and the second or third fingers and using the index finger on the finger piece 68 the car may be readily locked with one hand. In unlocking, one hand is all that is ever needed as the finger piece 68 is held down with the index finger while the lever is moved toward it by the thumb.

What I claim is:

1. The combination with a coincidental lock of the type in which the locking of the car breaks the ignition circuit and the unlocking of the car closes the ignition circuit, of means for delaying the breaking of the ignition circuit until the lock operating means is withdrawn from the lock.

2. The combination with a coincidental lock of the type in which the locking of the car breaks the ignition circuit and the unlocking of the car closes the ignition circuit, means for delaying the breaking of the ignition circuit until the lock operating means is withdrawn from the lock, said means including a rod movable into the path of the make-and-break mechanism, and a bell-
10 crank lever controlling said rod.
3. The combination with a coincidental lock of the type in which the locking of the car breaks the ignition circuit and the unlocking of the car closes the ignition circuit, means for delaying the breaking of the ignition circuit until the lock operating means is withdrawn from the lock, said means including a rod movable into the path of the make-and-break mechanism, and a bell-
15 crank lever controlling said rod, the two arms of said bell-crank lever being relatively movable.
4. The combination with a coincidental lock of the type in which the locking of the car breaks the ignition circuit and the unlocking of the car closes the ignition circuit, means for delaying the breaking of the ignition circuit until the lock operating means is withdrawn from the lock, said means including a rod movable into the path of the make-and-break mechanism, and a bell-
20 crank lever controlling said rod, the two arms of said bell-crank lever being relatively movable, one of said arms being limited in its movement by the presence of the key in the lock.
5. The combination with a coincidental lock of the type in which the locking of the car breaks the ignition circuit and the unlocking of the car closes the ignition circuit, means for delaying the breaking of the ignition circuit until the lock operating means is withdrawn from the lock, said means including a rod movable into the path of the make-and-break mechanism, and a bell-
25 crank lever controlling said rod, the two arms of said bell-crank lever being relatively movable, one of said arms being limited in its movement by the presence of the key in the lock.
6. In a steering post lock, a bolt, a key-controlled cylinder lock for withdrawing said bolt, a contact adapted to close the ignition circuit to the motor, resilient means yieldingly holding said contact in the path of said bolt when moving to unlocking position whereby when said bolt is withdrawn by said lock said contact will close the ignition circuit, and means movable into the path of said contact to prevent said resilient means causing said contact to follow said
- bolt to break the ignition circuit when said bolt is moved to locking position. 65
7. In a steering post lock, a bolt, a key-controlled cylinder lock for withdrawing said bolt, a contact adapted to close the ignition circuit to the motor, resilient means yieldingly holding said contact in the path of said bolt when moving to unlocking position whereby when said bolt is withdrawn by said lock said contact will close the ignition circuit, and means movable into the path of said contact to prevent said resilient means causing said contact to follow said bolt to break the ignition circuit when said bolt is moved to locking position, and key controlled means for withdrawing said last mentioned means from the path of said contact. 70
8. In a steering post lock, a bolt, a key-controlled cylinder lock for withdrawing said bolt, a contact adapted to close the ignition circuit to the motor, resilient means yieldingly holding said contact in the path of said bolt when moving to unlocking position whereby when said bolt is withdrawn by said lock said contact will close the ignition circuit, and means movable into the path of said contact to prevent said resilient means causing said contact to follow said bolt to break the ignition circuit when said bolt is moved to locking position, and key controlled means for withdrawing said last mentioned means from the path of said contact, said key controlled means including a manually controlled lever normally lying in position to prevent insertion of said key in said lock when said bolt is in forward or locking position. 80
9. In combination, a steering post, means adapted to prevent said post from turning, a key operated lock for moving said means from post locking position, means movable into position to close the key-slot of said lock, and an ignition circuit make-and-break mechanism which is operated to close said circuit by said first mentioned means. 90
10. In an automobile locking device, the combination of a key operated mechanism causing the unlocking of an automobile and the closing of the ignition circuit, and means controlled by the presence or absence of the key in its keyhole controlling the opening of the ignition circuit. 105
11. In combination, a bolt, a stem movable in the path of said bolt, a circuit make-and-break mechanism carried in part by said stem, means for limiting the movement of said stem independently of said bolt, a key controlled device for retracting said bolt and means set in motion by the withdrawal of said key from said device for rendering said first mentioned means inoperative to limit movement of said stem. 110
12. In combination, a steering post and

casing, an ignition circuit having a gap therein, a lock, a key therefor, a member movable to bridge said gap to complete the ignition circuit, means controlled by said lock for simultaneously locking said post to said casing and for moving said member to bridging position, means to move said member to position to open said gap, and means controlled by the presence of said key in said lock for holding said last mentioned means from acting until said key is removed from its position in said lock.

13. In combination, a member having angular movement, a bolt for locking said member against such movement, an electric circuit make-and-break mechanism, means for simultaneously moving said bolt to unlocking position and moving said mechanism to "make" position to close its circuit and an additional means for withholding movement of said mechanism to "break" position to open said circuit until after movement of the bolt to locking position.

14. In combination, a member having angular movement, a bolt for locking said member against such movement, an electric circuit make-and-break mechanism, means for simultaneously moving said bolt to unlocking position and moving said mechanism to "make" position to close its circuit, and for moving said bolt to locking position, and an additional means for preventing movement of said mechanism to "break" position to open said circuit, said bolt-moving-means consisting of a lock and a key therefor, and said additional means being controlled by the removal of said key from said lock.

15. In a device of the character described, a spring-pressed bolt, an ignition switch, a key operated lock for moving said bolt, and means connecting the lock and switch so that the key cannot be withdrawn from the lock without automatically operating the switch to break the ignition circuit.

16. In combination, a steering post, a key operated means to prevent said post from turning, means movable into position to prevent entry of said key in its key hole, and an ignition circuit make and break mechanism, means connecting both of said means with said mechanism so that the ignition circuit make and break mechanism is operated to close the circuit by movement of said key operated means and is moved to open said circuit by said key hole closing means.

17. The combination with a housing, a key operated member movable within said housing to lock a body with respect to said housing, and an electric circuit make and break mechanism connected to said member so that said mechanism is moved in one

direction by the unlocking of said body with respect to said housing and so that said mechanism may not be moved in the opposite direction without first moving said member to locking position, of means for delaying the movement of said mechanism in the last named direction until said key is withdrawn from said housing.

18. In a device of the character described, a bolt, an ignition switch, a key operated lock for moving said bolt and means connecting said lock and said switch so that the withdrawal of the bolt closes the ignition circuit and prevents withdrawal of the key while the bolt remains withdrawn.

19. The device of claim 18 including a member which prevents the switch from moving to circuit opening position upon movement of the bolt to locked position, until the key is withdrawn from the lock.

20. The combination with a sliding bolt steering post lock of the key operated coincidental type in which the ignition circuit is broken substantially simultaneously with the movement of the bolt into steering post locking position, and the ignition circuit is closed when the bolt is withdrawn, of means which is barred from completing its motion to break the ignition circuit by the presence of the key in the lock, whereby the breaking of the ignition circuit is delayed until after the key is withdrawn from the lock.

21. The combination with a key operated coincidental lock of the type in which the locking of the car breaks the ignition circuit and the unlocking of the car closes the ignition circuit, of means including a shaft and an arm on said shaft for delaying by reason of the striking of the arm against the key, the breaking of the ignition circuit until the key is withdrawn from the lock.

22. In a locking device for an automobile having an ignition circuit and an operative member movable during travel of the automobile, a housing, key operated mechanism within said housing causing the unlocking of said member and the closing of the ignition circuit, and means rendered inoperable by the presence of the key in the lock for controlling the opening of the ignition circuit.

23. In an automobile locking device, the combination with a key operated mechanism causing the unlocking of a movable part of the automobile and the closing of the ignition circuit, of means rendered inoperable by the presence of the key in the lock for controlling the opening of the ignition circuit, whereby the ignition circuit can be opened only when the key is out of the lock.

In testimony whereof I affix my signature.

CHARLES N. FAIRCHILD.
